ATTORNEY

UNITED STATES PATENT OFFICE.

ANNE LABORDE, OF NEW YORK, N. Y.

COMBINED HOT-WATER BOTTLE AND DOUCHE-BAG.

1,308,427.

Specification of Letters Patent.

Patented July 1, 1919.

Application filed December 15, 1916. Serial No. 137,139.

To all whom it may concern:

Be it known that I, ANNE LABORDE, a citizen of France, residing at New York city, borough of Manhattan, in the county of New 5 York and State of New York, have invented certain new and useful Improvements in Combined Hot-Water Bottles and Douche-Bags, of which the following is a specification.

10 This invention relates to medical appliances and more particularly to an improved hot water bottle and douche bag.

A primary object of the invention consists in the production of a hot water bag which 15 is particularly adapted for warming the feet, but it may be used for application to various parts of the body for warming the same in connection with the treatment of certain ailments or otherwise, and which will give a 20 larger surface exposure for warming purposes than any other bag heretofore provided for this purpose, while in addition, and without material modification of the bag, the same may be equipped for douching 25 purposes.

In connection with the use of the device as a foot bag, it is an object to overcome the difficulties and objections incident to the use of the ordinary hot water bottle caused by 30 the bulging thereof and collection of the water at one end of the bottle whereby its contacting surface area is considerably reduced, in addition to the fact that the ordinary hot water bottle cannot be applied to 35 the feet and be held thereto to warm both the bottom and the top portions and ankles of the feet at the same time.

In addition, it is an object of the invention to provide a hot water bag which can be applied to the feet while a person is in a reclining position upon a bed or when seated in a chair with the feet propped upon a cushion supported on another chair or the like so as to cause the bag to fit snugly to 45 the feet without materially exposing the same, and permitting both the top and bottom portions thereof to be warmed at the same time, also relieving the bag of undue pressure such as would undoubtedly cause 50 destruction thereof should it be necessary to support the weight of the lower limbs upon the bag.

A still further object of the invention is to provide novel fastening means for securing the bottle upon the feet of the patient or

user, the bottle comprising a construction adapted to produce a pair of communicating compartments, which when in use as a foot warmer, are adapted to be folded one upon the other to constitute an envelop to receive 60 and cover the feet at the top and bottom portions of the latter and around the ankles in contradistinction to a mere covering of the feet at one of said portions and in such a manner as to render it unnecessary to sustain the weight of the limbs upon the bottle, thereby obviating exposure of the feet to drafts and cool air, which would tend to negative any utility of the device as a foot warmer, which might otherwise be served. 65

With the above objects and others in view, as will appear as the description proceeds, the invention comprises the various novel features of construction and arrangements of parts which will be more fully described 70 hereinafter and set forth with particularity in the claims appended hereto.

Reference is had to the accompanying drawings forming a part of this application, in which like characters indicate the corresponding parts throughout the several views, and wherein,

Figure 1 is a plan view of a hot water bottle constructed in accordance with the invention, the bottle being opened out. 80

Fig. 2 is a sectional view taken on the line II—II of Fig. 1,

Fig. 3 is a sectional view taken on the line III—III of Fig. 1,

Fig. 4 is a sectional elevation showing the 90 method of application of the device as a foot warmer,

Fig. 5 is an enlarged fragmentary sectional view showing the manner of connecting the folded portions of the bottle for 95 securing the same upon the feet, and

Fig. 6 is a fragmentary sectional elevation showing a modification of the bottle for use as a douche bag.

As shown in the drawings, the improved 100 hot water bottle consists of two sections 7 and 8, of rubber or the like and of substantially rectangular outline, this producing the general outline of the bottle. These sections are composed of rubber and connected at their edge portions 9 by a binding 10, the connection being effected by vulcanizing or otherwise so as to make the bag waterproof. One end of the bottle is provided with a rectilinear edge 11, while the opposite end of

the bag is provided with a concavely arcuate edge 12 at either side of which said end is provided with convexly arcuate extensions 13, which are prolonged a greater distance 5 from the transverse center or axis of the bottle than the portion of the bag at the other side of said center so that the bag will fit around the ankles in a manner to be herein-after more fully explained.

10 With the sections 7 and 8 secured together at their edge portions as specified, a storage place is provided therebetween for receiving hot water or the like 14 and this space is divided into two communicating compartments 15 and 16, which are partially separated through a transverse connection or web portion 17 extending from one edge 18 to a point in spaced relation to the opposite edge 19, thereby providing a space 20 establishing 15 communication between the two compartments. At the transverse connecting or web portion 17, the opposite sections 7 and 8 are secured thereto as is more clearly shown in Fig. 2 of the drawings by vulcanizing or 20 otherwise, the embodiment illustrated, showing the sections 7 and 8 offset toward the connecting portion 17 as shown at 21 and 22, respectively, for connection with the portion 17, which latter is of sufficient width to permit 25 a proper folding of the bottle at the toes so as to conform accurately to the feet and lie snugly against the same. This construction also insures against bulging of the bag by the settling of the water at one side 30 thereof, that is, in one of the compartments 15 or 16, such as would cause displacement of the bag from the feet, render it impossible to fit the bag snugly to the feet, as well as impossible to entirely cover the feet. It 35 is believed that this will be understood by anyone familiar with the ordinary type of hot water bottle, as well as the fact that the bag will bulge out or become unduly distended at that end while the remaining end is only partially filled in the case of the bag 40 being filled to its capacity or if not filled entirely to its capacity, said latter end will be empty and, therefore, not serve any purpose 45 50 as a heating medium.

Intermediately of the longitudinal edge 18 the bag is provided with an extension 23 equipped with an eyelet 24 or other suitable means for suspending the device to permit 55 the same to drain through an outlet in a neck portion 25 provided intermediately of the opposite longitudinal edge 19. The neck portion 25 may be attached to or formed integral with the bottle proper and is provided 60 with an inclosed metallic and internally screw-threaded sleeve 26 adapted to receive a closure plug 27 for closing the filling and draining opening when the device is in use, but adapted to be removed when the device 65 is suspended by the eyelet 24 upon a

suitable nail or hook to permit the water or other fluid to entirely drain from the bottle after use.

As shown in Fig. 4 of the drawings, the device is so constructed that when a person 70 is sitting or reclining in a chair, the feet 28 may be propped upon a suitable pillow or cushion 29 so that the feet will extend substantially vertically erect, that is, in a natural position without imposing the exertion of muscular strain upon the legs to support the feet or necessitating that the weight thereof be supported by the bottle as is the case with devices heretofore provided. In this instance the part of the bag 80 provided with the compartment 16 will lie snugly against the bottoms of the feet and at the connecting or web portion 17 assisted by the eyelet 24 and the neck portion 25, the bag will fold gracefully and snugly over 85 the toes and the part of the bag providing the compartment 15 will lie snugly against the instep and ankles, the arcuate recess 12 and the convexly arcuate portions 13 serving to permit the bag to conform to the 90 ankles quite well up on the legs as well as providing slightly greater weight in the compartment 15 than in the compartment 16 so as to retain the bottle on the feet without the use of fastening means. Of course, if a 95 person is lying or reclining in bed, the feet will be similarly supported upon the mattress or a pillow disposed beneath the feet, to similar advantage, but if desired the bag adjacent to the compartment 15 may be provided 100 with opposite extensions or tabs 30 provided with spring balls 31 of ball or snap fasteners, while at opposite sides of the part providing the compartment 16, extensions, tongues or tabs 32 are provided 105 having coöperating socket parts 33, which completing the fasteners serve to permit the securing of the bottle upon the feet at the sides thereof by engaging said parts face to face, that is, with the tabs 30 and 32 in contact and extending directly outward instead of being rebent or curved as might be done if desired. Of course, it is to be understood that any suitable form of fastening means may be provided for connecting the 110 side edges of the bottle to hold the same on the feet and in contact with the feet at the outer sides so as to obtain the full effect of the heating medium and prevent the entrance of cool air or the formation of a 115 draft between the sections of the bag such as would tend to nullify the action of the heating medium. This form of connecting the side edges of the bottle as previously described, and which is possible by the construction shown in Fig. 1, is clearly shown in Fig. 5 of the drawings.

In the form of the invention shown in Fig. 6 of the drawings, in which a fragmentary part of a bag is shown in lieu of 120

the connecting portion 17, a connecting or web portion 34 is provided, but in this instance instead of extending to one side of the bag as shown in Fig. 1, said connecting portion terminates short of both sides so as to provide intermediate passages 35 and 36, establishing communication between the opposed compartments. In this instance the bag is provided with an additional neck portion 37 and a plug 38 closing the same, said plug being provided with a supporting ring serving as an operating member as well as means for suspending the bag from a hook or nail when draining the bag after use, or when the device is in use as a douche bag, as will be subsequently pointed out. The opposite side of the bag is provided with a neck portion 39 having an internally screw-threaded sleeve 40 adapted to receive the ordinary form of closure plug when the device is in use as a hot water bottle, either in connection with the feet as previously explained, or to serve as an applicant to any other part of the body with the advantage of a considerable increase in the area of the surface covered. When the device is in use to warm the feet, water may be supplied to the compartments from either side and the communicating spaces 35 and 36 will insure that the water will be distributed on both sides of the connecting or web portion or in the compartments, the remaining construction of the device being the same as illustrated in Figs. 1, 2, 3 and 4 of the drawings. In the use of two plugs, the draining of the bag will also be facilitated inasmuch as both plugs may be removed and a complete passage established through the bag open at both sides. On the other hand, when the device is in use as a douche bag, the closure plug is replaced by a plug 41 carrying a beaded tube 42 to which a discharge tube 43 is attached as in the ordinary form of douche bags, the nozzles adapted to be carried by the free end of the tube being of the ordinary or any preferred construction or shape consistent with the use thereof. This will provide three uses for the device instead of restricting its use as in the case of the ordinary form of hot water bag or bottle, or the ordinary douche bag, besides increasing materially the surface area of the body which may be covered by the application of the device in a spread condition as distinguished from the folded position of the device when in use as a foot warmer.

From the foregoing description, taken in connection with the accompanying drawings, the advantages of the construction and of the method of operation will be readily apparent to those skilled in the art to which the invention appertains and while I describe the principle of operation of the invention, together with the devices which I now consider to be the best embodiments

thereof, I desire to have it understood that the devices shown are merely illustrative, and that such changes may be made when desired as are within the scope of the device as claimed. 70

Having thus described my invention, what I claim as new and desire to secure by Letters Patent of the United States, is:

1. In a hot water bottle, opposed sides connected at their edge portions, said sides being of substantially elongated rectangular form with a rectilinear end and a concavely arcuate end provided with spaced convexly arcuate portions, a web portion transversely of the bottle intermediately of the length thereof, and a filling and draining means for the bottle. 75

2. In a hot water bottle, opposed sides connected at their edge portions, said sides being of substantially elongated rectangular form with a rectilinear end and a concavely arcuate end provided with spaced convexly arcuate portions, a web portion transversely of the bottle intermediately of the length thereof, a filling and draining means for the bottle, and suspending means for the bottle. 85

3. In a hot water bottle, opposed sides connected at their edge portions said sides being of substantially elongated rectangular form with a rectilinear end and a concavely arcuate end provided with spaced convexly arcuate portions, a web portion transversely of the bottle intermediately of the length thereof, and a pair of opposed filling and draining openings for the bottle. 95

4. In a hot water bottle, opposed sides connected at their edge portions, said sides being of substantially elongated rectangular form with a rectilinear end and a concavely arcuate end provided with spaced convexly arcuate portions, a web portion transversely of the bottle intermediately of the length thereof, and means for connecting the opposed edges of the bottle when 105 folded.

5. In a hot water bottle, opposed sides connected at their edge portions, said sides being of substantially elongated rectangular form with a rectilinear end and a concavely arcuate end provided with spaced convexly arcuate portions, a web portion transversely of the bottle intermediately of the length thereof, filling and draining openings for the bottle, said openings being 115 designed to receive closure plugs, and a douching implement having a tube adapted for connection in either of said openings. 120

6. A hot water bottle comprising opposed side portions joined at their edges to provide a receptacle, said side portions being connected by an intermediate web portion holding said sides offset toward each other, and filling and draining openings for the bottle adjacent said web portion. 125

7. A hot water bottle comprising opposed side portions joined at their edges to provide a receptacle, said side portions being connected by an intermediate web portion, 5 funnel-shaped necks at the side edges of the bottle and removable closures therefor, said necks being disposed intermediately of the length of the bottle, one end of said bottle having a rectilinear edge portion and the other end of said bottle having a concavely arcuate edge portion, as and for the purpose described.
8. A hot water bottle of rubber or the like, divided by a transverse narrow strip 15 with its opposite faces opposing the inner faces of the sides of the bottle and joining the opposed walls thereto in close proximity to each other to provide liquid-tight water holding compartments on either side thereof, 20 of, a passage connecting the compartments, and a plugged opening adjacent said passage.
9. A hot water bottle of rubber or the like divided by a transverse narrow strip between and joining the opposed walls thereto to provide liquid-tight water holding compartments on either side thereof, walls having a substantially rectangular outline and provided at one end with spaced convexly 25 arcuate portions and an intermediate concavely arcuate portion adapted when the device is folded and applied to the feet to
- conform to the ankles, passages connecting said compartments adjacent the edges of the bottle, and plugged openings adjacent 35 said passages.
10. A hot water bottle of rubber or the like divided by a transverse narrow strip joining the opposed walls to provide a folding line and liquid-tight water holding compartments on either side thereof, 40 passages connecting said compartments adjacent the edges of the bottle, and plugged openings adjacent said passages intermediately of the length of the bottle. 45
11. A hot water bottle of rubber or the like divided by a transverse narrow strip joining the opposed walls to provide a flat bending portion and liquid-tight water holding compartments, a pair of openings 50 provided adjacent the edges of the bottle opposite the ends of said bending portion for communication with the compartments interiorly of the bottle, passages provided to connect the compartments, a plug for one 55 of said openings, and a discharge tube for douching purposes connected in the other opening.

In testimony whereof I affix my signature in presence of two witnesses.

ANNE LABORDE.
